CUP-DISPENSING DEVICE

Harry Sebell, Boston, Mass.

Application January 27, 1934, Serial No. 708,609

3 Claims. (Cl. 312—55)

This invention relates to a device for dispensing folded cups one at a time from a stack of cups, and it has for one of its objects to provide a novel device of this type which is constructed so that at each actuation thereof the bottom cup of the stack will be invariably delivered.

The device comprises a container to hold a stack of folded cups, a manually-operated slide at the bottom of the container, and a cup-ejecting blade 10 carried by the slide and arranged so that when the slide is pulled forward said blade will engage the bottom cup of the stack and deliver it from the container. The device also has a novel construction whereby after each cup has been delivered the return movement of the cup-ejecting blade may be made without dragging the partially delivered cup back into the container again.

The type of folded cup which the device of this application is designed to dispense is one formed 20 from a paper blank having side wings which are folded over and adhesively united to make a lap joint, and which also has a bottom flap that is folded up and adhesively united to one side of the cup to form the bottom. One side of the cup 25 at the open end is longer than the other side to provide a lip or spout when the cup is used. In a cup having this construction there will be four thicknesses of paper at the bottom of the cup where the bottom flap overlies the side lap seam, 30 while at the top of the cup the lip or spout portion provides a single thickness of paper only. When, therefore, a stack of cups are piled up the quadruple thickness at the side of the stack where the bottoms of the cups are located builds up very 35 much faster than at the opposite side of the stack and it is difficult to handle a stack of cups of this type because the cups at the upper part of the stack will have quite an inclined position.

One of the objects of the present invention is 40 to provide a novel cup dispenser which is constructed so that the cups, such as above described, when arranged in a stack, will be prevented from becoming displaced when in the container notwithstanding that each cup has a quadruple thickness at one point at the bottom and a single thickness at the top. To provide for thus holding the cups properly in their stacked relation I employ a carton of special shape into which the cups are first placed in stack formation. This 45 carton filled with cups is then inserted in the container, and the carton remains in the container as the cups are dispensed. When all the cartons in the container have been dispensed then the empty carton is removed and another carton filled with 50 cups is deposited in the container, the carton

serving to hold the cups in proper position for the operation of the dispensing device.

The features of the invention will be hereinafter set forth and then pointed out in the appended claims.

In the drawings wherein I have shown a selected embodiment of my invention, Fig. 1 is a vertical sectional view through a cup dispenser embodying my invention;

Fig. 2 is a fragmentary sectional view showing the operation of ejecting a cup;

Fig. 3 is a section on the line 3—3, Fig. 1;

Fig. 4 is a fragmentary view looking down onto the bottom of the casing and showing the ejecting blade and slide;

Fig. 5 is a similar view showing the position of the blade as it is ejecting a cup;

Fig. 6 is a section on the line 6—6, Fig. 4;

Fig. 7 shows the style of cup which this device is designed to dispense;

Fig. 8 is an enlarged section on the line 8—8, Fig. 7;

Fig. 9 is a perspective view of a carton containing cups to be dispensed;

Fig. 10 is a vertical sectional view through the carton illustrating diagrammatically the manner in which the cups are stacked therein;

Fig. 11 is a plan view of the carton;

Fig. 12 is a top view thereof;

Fig. 13 is a view through the folded cup on the line 13—13, Fig. 7.

The cup which this device is specially designed to dispense is indicated at 2 and is illustrated in Fig. 7. It is a folded paper cup made from a blank having the side wings 40 and 41 and a bottom flap member 8, the side wings 40 and 41 being folded over and having their edges adhesively united with a lap joint as shown at 7 and the bottom flap 8 being turned up and adhesively united to the side of the cup. The cup has the open top and one side of the cup is longer than the other as shown at 42, the longer side forming a sort of spout, when the cup is being used.

In a cup of this type there will be four thicknesses of paper at the bottom at the point 43 where the bottom flap 8 overlies the lap seam 7, while at the top of the cup the spout portion 42 presents a single thickness of paper.

The dispensing device herein illustrated comprises a container 1 adapted to hold a stack of the folded cups 2, said container being shown as having an open top into which the cups may be delivered and a closure 3 for closing the open top.

When a large number of folded cups 2 are piled

in the form of a stack of cups with the bottoms of the cups all arranged in the same direction the vertical dimension of the side of the stack where the bottoms of the cups occur will be much 5 greater than the opposite side because each cup has four thicknesses of paper at the bottom thereof at the point 43, while at the top each cup has only the single thickness of the spout portion 42. As a result if the cups are piled into 10 a stack of any height the upper cups of the stack will have such an inclined position that it will be difficult to retain them in place.

To partially overcome this difficulty I propose to make the container 1 with an inclined bottom 15 4 and to arrange the cups in the container with the thicker bottom portion at the lower end of the incline. The container is also provided with a delivery opening 5 at its front at the lower end of the inclined bottom, through which opening 20 the cups are delivered one by one as will be presently described.

As a further means for holding the cups in place I propose to employ a carton 44 which is adapted to receive a stack of cups and which in 25 turn is designed to be deposited in the container 1. This carton 44 has the inclined bottom 45 which fits the inclined bottom 4 of the container and the top 46 of the carton is also inclined but in an opposite direction from the bottom. As a 30 result the front 47 of the carton will be considerably longer than the back 48.

The carton can be opened at the top and the top is closed by side flaps 49 which are folded inwardly to overlap each other and front and 35 rear flaps 50 and 51 are also folded to overlap each other and can be fastened together in usual way by means of tabs 52 formed on the rear flap 51 adapted to be inserted through openings 53 formed in the front flap 50. This carton is 40 designed to be filled with a stack of cups placed therein with the side having the folded flap 8 and the side seam 7 on the under side of each cup and with the bottoms of the cups directed toward the front of the carton. This peculiar 45 shape of carton will fit the stack of cups because of the fact that each cup has four thicknesses of paper at the bottom end thereof which is at the front 47 of the carton and only one thickness at the other end, which is at the back 48 of the 50 carton.

The carton is provided at its lower corner with a discharge opening 54 which aligns with the cup-delivery opening 5 of the container and it is also formed in its bottom with a slot 55 for purposes presently to be described.

The cups are dispensed one by one from the carton and container through the medium of a slide 10 which is situated beneath the bottom 4 of the container and is mounted to slide in suitable guideways 12 secured to said bottom. This slide 10 is provided at its front end with a finger pull 11 by which it may be drawn forwardly and it is acted on by a return spring 13 which normally holds it in retracted position and which 60 resists forward pulling movement thereof. This spring is anchored at one end to a projection 56 secured to the bottom 4 of the container and at the other end to a finger 57 with which the slide 10 is provided. The bottom 4 of the container is 65 provided with an opening or slot 14 which mates the slot 55 in the bottom of the carton.

The slide 10 carries on its upper side a cup-ejecting blade 15 which operates through the slots 14 and 55 and which is constructed so that 70 when the slide is pulled forward this blade will

engage the edge 9 of the bottom flap 8 of the bottom cup of the stack and will partially deliver said cup through the openings 54 and 5 as shown in Fig. 2. The blade 15 is pivotally connected to the slide for which purpose it is provided with two trunnions 16 that have a pivotal bearing in ears 17 rising from the slide. 18 is a stop flange carried by the slide and which limits the backward swinging movement of the blade 15, and 19 is a similar stop flange which limits the forward swinging movement thereof. The upper portion 3 of the blade is shown as bent forwardly. When the slide 10 has been returned to its rearward position as shown in Fig. 1 the blade 15 10 will have its forward or inoperative position also 15 shown in Fig. 1 and in this position said blade is situated in the rear of the edge 9 of the bottom cup.

Means are provided whereby when the slide 10 is pulled forwardly the blade 15 will, during 20 the initial forward movement of the slide 10, be swung from its forward inoperative position shown in full lines Fig. 1 into its upright operative position shown in dotted lines in Fig. 1. As the blade swings into its dotted line position the 25 upper end 30 thereof moves upwardly and is pressed firmly against the bottom cup. Continued movement of the blade after it has reached its upright operative position brings the upper edge thereof against the edge 9 of the bottom cup 30 so that during the final forward movement of the slide the bottom cup will be dragged forward by the blade and will be partially projected through the openings 54 of the carton and 5 of the container. This places the bottom cup in 35 position where the bottom edge can be readily grasped by an operator for the purpose of withdrawing it completely from the container. The cups above the bottom cup of the stack are prevented from being withdrawn by engagement 40 with the front wall of the carton.

When the slide is released the spring 13 will return it to its backward position shown in Fig. 1 and during this return movement of the slide the blade swings forwardly into its inoperative 45 position and the rounded portion 30 moves back in contact with the bottom cup of the stack. If the slide is released before the partially delivered cup is completely withdrawn from the container the blade will frictionally engage such partially delivered cup during its backward movement but because of the rounded shape of the top of the blade this backward movement thereof will take place without any tendency to drag the partially delivered cup back into the container.

In order that the cup-ejecting blade 15 may function properly it is important that it should always have the upright operative position when the slide is pulled forwardly so as to place the upper edge thereof in proper position to engage the edge 9 of the bottom cup, and it is also desirable that the blade should have its forward inoperative position when the slide moves backwardly so as to prevent the slide from dragging the partially delivered cup back into the container. To ensure that the blade will always have the proper position I have provided a spring arm 21 which is secured to the bottom 4 and which frictionally engages the side of the blade 15. The point of engagement between this spring 60 arm and the blade is above the pivot of the blade and hence as the slide is pulled forward the frictional engagement of the arm with the blade operates to turn the blade into its upright position 65 during the initial forward movement of the 70 slide. The blade 15 is provided with a stop flange 75 which limits the forward movement of the blade 15 and which is shown in dotted lines in Fig. 1.

slide and then maintains the blade in such position during the continued forward movement of the slide. When the slide is released the drag of the spring arm on the edge of the blade will 5 cause the blade to swing forwardly into its inoperative position during the initial movement of the slide and will maintain the blade in this position for the continued backward movement of the slide.

10 22 indicates stops depending from the bottom 4 and which limit the return or spring-impelled movement of the slide 10.

The use of the carton 44 is important because if the container was filled with cups placed loosely 15 therein and without being confined in a carton the top cups of the stack would be at such an inclination that they would tend to slide down back of the stack and interfere with the operation of the device. By employing the carton, 20 however, the upper cups of the stack are retained in position and are prevented from becoming displaced and thus interfering with the proper operation of the device. The carton has the further advantage that it facilitates the loading 25 of the container with a stack of cups. These cups can be packed in the cartons at the factory and the filled cartons shipped to the locations where the containers are used. When the cups in a container need replenishing it is a simple 30 matter to remove the empty carton from the container and place therein a filled carton.

I claim:

1. A cup dispenser comprising a casing to hold 35 a stack of folded cups and having an inclined bottom provided with a slot and also having a cup-delivery opening, a manually-operated slide beneath the bottom, a cup-delivery blade pivoted to said slide and extending through said slot and adapted to engage the bottom cup of the stack as 40 the slide is pulled forward thereby to eject said cup through said opening, and means carried by the bottom and frictionally engaging said blade

to swing the latter into a forwardly-inclined position during the retracting movement of the slide and to swing said blade into an upright cup-engaging position during the forward movement of the slide.

2. A cup dispenser comprising a casing to hold a stack of folded cups and having an inclined bottom provided with a slot and also having a cup-delivery opening, a manually-operated slide beneath the bottom, a cup-delivery blade pivoted to said slide and extending through said slot and adapted to engage the bottom cup of the stack as the slide is pulled forward thereby to eject said cup through said opening, and a resilient arm carried by the bottom and having frictional engagement with the side edge of the blade, said arm operating to swing the blade into its upright cup-engaging position during the initial forward movement of the slide and into a forwardly-inclined inoperative position during the 20 initial retracting movement of the slide.

3. A cup dispenser comprising a container to hold a stack of folded cups, each of which has a transversely-extending shoulder, said casing having a slot in its bottom and also a cup-delivery 25 opening at its front, a manually-operated slide beneath the bottom, a cup-delivery blade pivoted to said slide and extending through said slot, and means frictionally engaging the blade and operating to swing it into a forwardly-inclined 30 inoperative position during the initial retracting movement of the slide and to swing said blade into an upright cup-engaging position during the initial forward movement of the slide, whereby as the slide is pulled forward the upper 35 edge of the blade is swung into a position to engage the shoulder of the bottom cup during the initial forward movement and the cup is partially ejected through the cup-delivery opening during the remainder of said forward movement. 40

HARRY SEBELL.
